ATTORNEY

UNITED STATES PATENT OFFICE

JESSE TUTHILL, OF CHILlicothe, ILLINOIS

FOLDING UMBRELLA

Application filed May 14, 1928. Serial No. 277,496.

My present invention has reference to an improvement in folding umbrellas.

The primary object is the provision of a folding umbrella having an improved construction of jointed ribs and spreaders connected with the joints of the outer rib sections, of such construction and arrangement as to permit of the parts being folded to reduce the size of the umbrella so that the same can be conveniently carried in the hand or in the traveling case of the user.

To the attainment of the foregoing the invention consists in the invention as herein-after described and definitely claimed.

15 In the drawings:—

Figure 1 is a side elevation of a sufficient portion of an umbrella construction to illustrate my improvement, parts being broken away and parts in section.

20 Figure 2 is a similar view showing the parts moved to the first stage in the collapsing of the umbrella.

Figure 3 is a detail elevation to illustrate the next step in the folding of the umbrella.

25 Figure 4 is a view showing the umbrella folded, and the handle portion of the stick removed.

Figure 5 is a detail elevation of the handle portion of the stick.

30 Figure 6 is an enlarged elevation looking toward the joint of the ribs of the umbrella.

Figure 7 is a top plan view of the rib-spreader joint.

Figure 8 is a view substantially similar to 35 Figure 6 but illustrating a modification.

Figure 9 is an elevation showing the ribs and the spreader therefor when the umbrella construction disclosed by Fig. 8 is closed.

40 The stick of the umbrella includes an upper section 1, and a lower section 2 that carries a handle 3. The stick section 2 has a reduced threaded extension which is screwed in the socket of the section 1.

45 Fixed on the outer end of the stick section 1, inward of the ferrule thereon there is a top-notch 4 and to this top-notch there is pivotally secured the ribs. In the showing of the drawings I have deemed it necessary to illustrate only one of such ribs. As 50 closed by the drawings the rib comprises an

inner section 5 and an outer section 6. The inner section 5, at the outer end thereof, is preferably thickened to form the same with a lug extension 7 which, from its outer end is widened, as at 8, and provided on one of its faces with a laterally extending pin or lug 9. The outer rib section is provided with a similar lug 10, which in the preferred embodiment of the invention is formed with a centrally arranged depending ear 11 that is pivoted, as at 12, to the depending portion 8 of the lug 7.

Pivoted, as at 13, to the inner end of the lug 10 there is the bifurcated end of a spreader rod 14. The spreader rod is pivotally secured to the usual runner 15 that is arranged for movement on the stick, which runner is notched in the usual manner to engage the upper deppressible spring catches 16 in the stick member 1 and the lower deppressible catch member 17 in the stick section 3.

When the runner is moved outwardly on the stick and is engaged by the upper catch 16 on the stick the spreader rod 14 will be moved to the position illustrated in Figure 1 of the drawings and will cause the swinging of the rib sections 5 and 6 on their pivot 12 to cause the pin or stop 9 to be brought into contact with the shoulder 18 on the lug 10. The rib sections are thus effectively held in longitudinal alinement. By moving the runner downwardly on the stick the outer rib section 6 may be swung toward and almost against the inner rib section 5. When the runner is again moved outwardly on the stick, it may be moved beyond the upper catch 16 on the stick section 1. Thereafter the handle carrying portion of the stick may be unscrewed from the section 1 and be inserted in the fabric of the folded umbrella.

In Figures 8 and 9 the outer rib section 19 is connected to the inner rib section 20 by a bail or like element 21 that passes through the sides of both of the rib sections. The outer rib section 19 is formed with an extension 21' which is notched, as at 22, to receive the inner arm of the bail 21 therein when the rib sections are in spread condition. To the extension 21' there is pivotally secured, as at 23, the angle end 24 of the spreader member

25. The operation of this arrangement is similar to that previously described.

The simplicity and advantages of my construction will it is believed be fully understood and appreciated by those skilled in the art when the foregoing description has been carefully read in connection with the accompanying drawings, but obviously I do not wish to be restricted to the precise details herein set forth and, therefore, hold myself entitled to make such changes therefrom as fairly fall within the scope of what I claim.

Having described the invention, I claim:—

In a folding umbrella having a staff, ribs 15 having their inner ends pivoted on the outer portion of said staff and comprising inner and outer sections, a relatively thick elongated member attached to the outer end of the inner rib section and formed to provide 20 an off-set lug, a pin projecting laterally from said member and at a right angle to said lug, an elongated member secured to the adjacent end of the outer rib section and formed to provide a centrally located apertured lug projecting from one edge of the 25 member and pivotally mounted upon the first mentioned member, and a spreader rod having sliding and pivotal connection with said staff, and having an outer off-set bifurcated 30 extremity pivotally connected with the inner end of said member carried by the outer rib section, whereby the rib sections and rods can be arranged substantially parallel with 35 said staff or extended therefrom for use with the last mentioned member engaging said pin with said rib sections arranged in end to end relation.

In testimony whereof I affix my signature.

JESSE TUTHILL.
